UNITED STATES PATENT OFFICE

BENJAMIN C. MYERS, OF TRENTON, NEW JERSEY

DESIGN FOR AN ADVERTISING NOVELTY

Application filed July 6, 1931. Serial No. 40,434. Term of patent 14 years.

To all whom it may concern:

Be it known that I, BENJAMIN C. MYERS, a citizen of the United States, residing at Trenton, in the county of Mercer and State of New Jersey, have invented a new, original, and ornamental Design for an Advertising Novelty, of which the following is a specification, reference being had to the accompanying drawings, forming part thereof.

In the drawings:

Fig. I is a frontal perspective view of an advertising novelty, showing my new design; and

Fig. II is a perspective view of the rear of the novelty.

I claim:

The ornamental design for an advertising novelty, as shown.

BENJAMIN C. MYERS.
